J. A. BROWNE

DOUBLE HARDY

Filed Nov. 6. 1923

WITNESS:

Ernest Turner

INVENTOR
J. A. Browne

BY
O. Goldbury, ATTORNEY

UNITED STATES PATENT OFFICE.

JOSEPH A. BROWNE, OF MELROSE, MONTANA.

DOUBLE HARDY.

Application filed November 6, 1923. Serial No. 673,230.

To all whom it may concern:

Be it known that I, JOSEPH A. BROWNE, a citizen of the United States, residing at Melrose, in the county of Silver Bow and

5 State of Montana, have invented a new and useful Double Hardy, of which the following is a specification.

My invention relates to improvements in double hardies for blacksmiths, in which 10 the lower hardy is equipped with vertical channel bars for the guidance of the upper hardy.

The objects of my invention are to produce a tool which is simple to manufacture; 15 which cuts the metal simultaneously on two sides; which operates with the same ease as a single hardy; and which can be quickly taken to pieces for sharpening purposes.

Other objects and advantages are to be 20 found in the construction and arrangement of parts as will be described in the specification and particularly pointed out in the appended claims.

I attain these objects with the mechanism 25 illustrated in the accompanying drawing, in which—

Fig. 1 is a side elevation of the entire hardy;

Fig. 2 is a section through Fig. 1 along 30 the line 2—2;

Fig. 3 is a section through Fig. 1 along the line 3—3.

Similar numerals refer to similar parts 35 throughout the several views.

The lower hardy 1 consists of a flat rectangular steel plate set on edge, and provided with the customary shank 2 to be inserted in the anvil 3. The upper edge of the hardy is tapered to a cutting edge.

40 Pressed against the vertical ends of the lower hardy are the two channel bars 4, 4' which serve as guide ways for the upper hardy 5. The upper hardy is sharpened at the lower edge, while the upper edge has the corners 45 cut at 6 to allow for brooming during use.

A band 7 holds the channel bars to the lower hardy. The band passes through an eccentric 8 having a handle 9, and can thereby be instantly tightened or loosened. A groove 50 10 in one channel bar holds the band in proper position. The eccentric is prevented from sliding up or down by a groove 11 in the other channel bar. To give the band 7 a certain amount of elasticity, said band is 55 slightly curved as indicated at 12 in Fig. 1.

This elasticity insures a smoother working for the eccentric, and affords a more satisfactory connection under the vibrations to which hardies are usually subjected.

In operation the blacksmith removes the 60 upper hardy, places his iron 13 on the sharp edge of the lower hardy, reinserts the upper hardy, and then severs the iron by the blows of his hammer on the upper hardy.

When the cutting edge of the lower hardy 65 becomes dulled and needs sharpening, the handle 9 is thrown into the dotted position 14, the channel bars 4 and 4' can then easily be withdrawn and the hardy sharpened in any suitable way.

70 It is apparent that damage to the cutting edges of the hardies would result if the latter were permitted to meet too closely, this is avoided by the introduction of a movable cushioning block 15 in the channel bar 4. 75 The channel bar is provided with a slot 16 and the cushioning block is held in the channel by a stem 17 preferably in the shape of a countersunk rivet extending from the block through the slot and carrying on the outside a washer 18. The hardies should have the corners which come in contact with the cushioning block recessed to an amount sufficient to permit approach of the two cutting 80 edges for a complete severance of the interposed iron 13 without actually touching each other. The recesses are indicated by the numerals 19 and 20 in Fig. 1.

85 The slot 16 should be long enough so that the cushioning block will adjust itself to 90 hardies of different heights.

In the foregoing specification a preferred 95 form of construction has been described, it should however be understood that minor changes in detail are considered to lie within the scope and purview of my invention, providing I do not violate the spirit and principle thereof.

I claim:

1. A double hardy, comprising a lower 100 hardy, an upper hardy, channel bars attached to the end surfaces of the lower hardy, and quick-detachable means to hold the channel bars to the lower hardy.

2. A double hardy, comprising a lower 105 hardy, an upper hardy slidably mounted above the lower hardy, channel bars to guide the upper hardy attached to the lower hardy, and an elastic band encircling the lower hardy and the channel bars. 110

3. A double hardy, comprising a lower hardy, an upper hardy, channel bars attached to the lower hardy, an elastic band encircling the channel bars and the hardy, 5 and an eccentric inserted in said band and pressing said channel bars against the lower hardy, whereby said channel bars can be quickly attached or removed.

4. In a double hardy, the combination of 10 two vertically disposed hardies having their cutting edges turned toward each other, with quick-detachable guiding means for the upper hardy attached to the lower hardy, and a cushioning block between the two hardies.

15 5. In a double hardy, the combination of two vertically disposed hardies having their cutting edges turned toward each other, with vertical channel bars attached to the end surfaces of the lower hardy to guide

20 the upper hardy, an elastic band encircling the lower hardy and the channel bars, and a cushioning block between the two hardies.

25 6. In a double hardy, the combination of two vertically disposed hardies having their cutting edges turned toward each other, with vertical channel bars attached to the end surfaces of the lower hardy, a band encircling the lower hardy and the channel bars, an eccentric cooperatively connected

with the band to tighten or loosen said channel bars, and a cushioning block between the two hardies. 30

7. In a double hardy, the combination of two vertically disposed hardies having their cutting edges turned toward each other, 35 with quick-detachable channel bars to guide the upper hardy attached to the lower hardy, and a cushioning block between the two hardies, said cushioning block being slidably mounted in one of said channel bars. 40

8. In a double hardy, the combination of two vertically disposed hardies having their cutting edges turned toward each other, 45 with quick-detachable channel bars to guide the upper hardy attached to the end surfaces of the lower hardy, one of said channel bars having a longitudinal slot in the web, a cushioning block slidably mounted in the channel of the channel bar, a washer, 50 and a stem extending through said slots between cushioning block and washer, the cutting edges of the hardies adjacent to the cushioning block being recessed for the reception of said cushioning block. 55

Signed by me at Melrose, Montana, this 24th day of October, 1923.

JOSEPH A. BROWNE.
